The ornamental design for a lid, as shown and described.

DESCRIPTION

FIG. 1 is a top perspective view of a lid;

FIG. 2 is a front view of the lid shown in FIG. 1;

FIG. 3 is a rear view of the lid shown in FIG. 1;

FIG. 4 is a left side view of the lid shown in FIG. 1;

FIG. 5 is a right side view of the lid shown in FIG. 1;

FIG. 6 is a top view of the lid shown in FIG. 1; and,

FIG. 7 is a bottom view of the lid shown in FIG. 1.

The broken lines are shown for the purpose of illustrating environmental structure and parts of the article that form no part of the claimed design.
